PORTABLE ELECTRIC BAKING OVEN

Daniel D. Dillingham and Richard F. Dillingham, Abilene, Tex., assignors to Master Corporation of Texas, Abilene, Tex., a corporation of Texas

Filed July 1, 1963, Ser. No. 75,610

Term of patent 14 years

(Cl. D81—10)

FIG. 3

FIG. 5

FIG. 4

FIG. 6

FIG. 1 is a top plan view of an electric baking oven embodying our new design;

FIG. 2 is a front view of the same;

FIG. 3 is a left hand side view of the same, with the front opening tray partially pulled out; both sides of the oven are substantially the same in appearance;

FIG. 4 is a rear view of the same;

FIG. 5 is a bottom plan view of the same; and

FIG. 6 is a three-quarter front perspective view of the same.

We claim:

The ornamental design for a portable electric baking oven, as shown and described.
